(57) CLAIM

The ornamental design for a slipper as shown and described.

DESCRIPTION

FIG. 1 is a perspective view of a slipper showing my new design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

FIGS. 1-7 depict a right foot slipper of a pair of slippers; a left foot slipper of the pair of slippers, which is a mirror image of the preceding embodiment, is also claimed but not shown.

The broken lines in the drawings represent portions of the right foot slipper that form no part of the claimed design.
